GEORGE D. SWEIGERT, OF MARTIC TOWNSHIP, PENNSYLVANIA, ASSIGNOR
TO HIMSELF, JOHN SWEIGERT, AND FELIX W. SWEIGERT.

Letters Patent No. 72,113, dated December 10, 1867.

IMPROVEMENT IN PORTABLE FENCE.

The Schedule referred to in these Letters Patent and making part of the same.

TO ALL WHOM IT MAY CONCERN:

Be it known that I, GEORGE D. SWEIGERT, of Martic township, in the county of Lancaster, and State of Pennsylvania, have invented a new and useful combination or mode for constructing a Portable Fence; and I do hereby declare that the following is a full and exact description thereof, reference being had to the accompanying drawings, making part of this specification, in which—

Figure 1 gives a view of several panels of this fence in line.

Figure 2, the same, on a reduced scale, surrounding a stack in the field.

Figure 3 shows a corner, also detached figures of each part employed.

Figure 4 shows how pales can be applied to the upper and lower rails, if desired.

The nature of this fence consists in each piece employed being independent, requiring no nail or screw-fastening, and can be set up or taken apart, so that the rails, posts, base-plates, and every separate portion can be packed away or piled up in a small space, making a neat and durable fence, which can be set straight, zigzag, or at any angle, each panel moving on the post, as a pivot, in any direction.

To enable any one skilled to make and use my invention, it is only necessary to say that the posts C are of rolled one-inch iron, of the desired length. The ferrules or sleeves D are cast of uniform length and thickness, with an inch bore. E, an ornamental head; F, a washer; and G, a key or wedge. The rails B being cut of a uniform length, scarfed-out half way, on the reverse sides of the ends, and an inch hole bored through the projecting ends, centrally, the fencing materials are all ready, including the base-plate A, also cast, with a hole in the central raised and narrowed portion, as shown.

To erect the fence, all that is necessary is to lay down the foot or bed-plate A, insert the round iron post C; key it fast. Slip down a washer or ring, F; key it fast with a key, G. The lower rail is now put in place, by inserting the top of the posts into the holes on each scarfed end, working in the direction so that when the first rail is pressed down upon the washer or ring the projection will be on the under side. When the lower rails are in place, a sleeve or ferrule, B, is slipped down upon the lower rails, united by their scarfed ends, which, when slightly rounded, will turn in any direction on the post, as on a pivot. So in succession the rails are put in place with the intervening supports D. The projecting top is ornamented with a washer, keyed on, and an ornamental head, E, if desirable. The facility with which the fence can be set up, turned in any direction, so as to surround grain stacks, set zigzag or otherwise, besides its neatness, presents many advantages.

When we consider the durability and cheapness, as well as the convenience of using the castings and wrought-iron posts in combination with the wooden rails, the small advance in price over many other portable fences will be but a slight objection, if any at all, to the adoption of this arrangement. The steps can be inserted in the soil, or held by a wooden peg, to give greater firmness, or to accommodate the same to inequalities in the ground.

I am aware of the numerous combinations and arrangements of portable fences patented; but I am not aware of any combination of this specific arrangement; nor do I claim any portion of the same, separately considered, apart from the combination of the whole, as herein shown and specified.

What I claim as my invention, is—

A portable fence, combined of round wrought-iron posts C, bed-plate A, rails B, scarfed, and applied with intervening ferrules D, head and bottom washers F, all arranged in the manner and for the purpose specified.

GEORGE D. SWEIGERT.
